US00D884668S

(12) **United States Design Patent** (10) **Patent No.:** **US D884,668 S**
(45) **Date of Patent:** **** May 19, 2020**

(54) **SPEAKER**

- (71) Applicant: **Samsung Electronics Co., Ltd.**, Suwon-si (KR)
- (72) Inventors: **Jaehyung Kim**, Gwangju-si (KR); **Dae Kyung Ahn**, Namyangju-si (KR); **Kwanhee Lee**, Seoul (KR)
- (73) Assignee: **Samsung Electronics Co., Ltd.**, Suwon-si (KR)
- (**) Term: **15 Years**
- (21) Appl. No.: **29/662,355**
- (22) Filed: **Sep. 5, 2018**

(30) **Foreign Application Priority Data**

- Apr. 27, 2018 (KR) 30-2018-0019892

(57) **CLAIM**

We claim the ornamental design for a speaker, as shown and described.

DESCRIPTION

FIG. 1 is a front perspective view of a speaker showing our new design according to a first embodiment;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a speaker showing our new design according to a second embodiment;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a rear perspective view thereof.

The broken lines in the figures depict portions of the speaker which form no part of the claimed design.
